UNITED STATES PATENT OFFICE.

JOHN GRATZ AND PETER HAGEDORN, OF CHICAGO, ILLINOIS.

CIGAR-CUTTER.

SPECIFICATION forming part of Letters Patent No. 291,509, dated January 8, 1884.

Application filed February 17, 1883. (No model.)

To all whom it may concern:

Be it known that we, JOHN GRATZ and PETER HAGEDORN, citizens of the United States of America, residing at Chicago, in the county 5 of Cook and State of Illinois, have invented a new and useful Improvement in Cigar Cutter and Register, of which the following is a specification, to wit:

This invention relates to cigar-cutters; and 10 it consists in the construction and arrangement of parts as hereinafter more fully described and claimed.

In order to enable others skilled in the art 15 to which our invention appertains to make and use the same, we will now proceed to describe its construction and operation, referring to the accompanying drawings, in which—

Figure 1 is a perspective view of our invention; Fig. 2, an end elevation of the same; 20 Fig. 3, a plan view with the dials removed from the register; and Fig. 4 is a cross-section through one of the dials and ratchet-toothed registry-wheel.

A represents a block or frame provided with 25 the usual groove, *a*, for the reception of the stock to be cut, and an adjustable gage, *A'*, and scale *a'*, for regulating the length of the cigars to be cut. At one end the block *A* is provided with a metal bearing-plate, *B*, having 30 a beveled semicircular opening, *b*, opposite the end of the groove *a*, against which the knife operates, and pivoted to the other side of this plate is an operating-lever, *B'*, as seen in the drawings.

Pivoted to the plate *B* at *c*, above and in front of the pivot of the lever *B'*, is the knife *C*, formed, as shown, of oval form, or having its cutting-edge describing a parabolic curve, *c'*. This knife is pivoted near one end, and has its upper 40 end formed with an open slot, *c''*, in which works a stud, *b'*, upon the hand-lever *B'*. It will thus be seen that by reason of the peculiar shape of its cutting-edge, and its being pivoted above and at one side of the lever, the knife, in passing 45 the opening *b* of the bearing-plate, is given a peculiar drawing cut, which severs the end of the cigar clearly and without breaking the wrapper or filling. Outside of the bearing-plate is secured a guide-piece, *C'*, which guides 50 the knife and keeps it rigidly in place while in operation, at the same time forming a support for the outer end of the stock while be-

ing operated upon. The pivot *b''* of the lever *B'* passes through the plate *B* and extends a short distance beyond it, and is supplied with a 55 coiled spring, *B''*, which returns the lever and knife to their highest or normal position after being depressed. The inner end of this pivot *b''* is provided near one edge with a wrist-pin, *d*, upon which is a pawl, *D*, having its lower 60 end passing down into the register mechanism and engaging therewith. The block *A* is recessed just in rear of the plate *B*, and provided with one or more dials and registering mechanism, by which the number of cigars 65 operated upon is accurately recorded. In the present instance two of these dials are shown, one of which records single cigars and the other hundreds. The dial *E* is divided into a hundred spaces or divisions, and provided 70 with a hand, *e*, upon a central hub or shaft, *e'*, which passes through the block, and is provided with a handle, *e''*, upon its under side, by which the hand may be turned to set it at the first division after having been used. Upon 75 this hub, below the dial, is a wheel, *E'*, provided upon its outer edge with one stud or tooth, *e''*, and upon its upper side with a hundred ratchet-teeth, *e'''*, with which the pawl *D* engages as the device is operated, moving the 80 wheel forward one notch for each operation of the lever *B'*.

F is a second dial, divided into twenty-five spaces, intended to register hundreds, and having a hand, *f*, hub *f'*, having a handle, *f''*, 85 and a wheel, *F'*, formed with twenty-five teeth, with which the one tooth or stud on the adjoining wheel will mesh. As the lever *B'* is depressed, its pivotal shaft is rotated, and the pawl *D* throws the wheel *E* forward one notch, 90 registering one upon the dial above. When this wheel has been entirely revolved, the stud upon its periphery strikes and turns the other one, *F'*, and registers one upon the second dial, thus registering single cigars upon one and 95 hundreds upon the other.

While we have described a mechanism adapted to register upon two dials the number of cigars cut, it is obvious that any number may be used, divided into any desired number of 100 spaces; and we may also use gearing of different construction for operating the hands, the ones described being only one of the modes by which this may be done.

Having thus fully described our invention, what we claim as new, and desire to secure by Letters Patent, is—

The combination, with the box or block A, 5 containing a registering mechanism, and provided with a groove, *a*, and an adjustable gage, A', of the plate B, secured to one end of said box, and having a beveled semicircular opening, *b*, the knife C, pivoted to said plate and 10 having a slot, *c*², the hand-lever B', having a pivot, *b*², passing through the plate B, and provided with a stud, *b'*, engaging the slotted

knife C, the spring B² on the pivot *b*², for returning the knife, and means for actuating the registering devices at each stroke of the knife, 15 all substantially as shown and described.

In testimony whereof we affix our signatures in presence of two witnesses.

JOHN GRATZ.
PETER HAGEDORN.
